SEAL ARRANGEMENT FOR FLOATING ROOF
Reign C. Uim, Schererville, Ind., assignor to Union Tank
Car Company, Chicago, Ill., a corporation of New
Jersey

Filed June 18, 1959, Ser. No. 821,247
7 Claims. (Cl. 220—26)

The invention relates to sealed storage tanks of the floating roof variety, and particularly to a novel pressure seal arrangement therefor.

It is a primary object of the invention to provide a unique flexible tube arrangement to seal the annular space between a sealed storage tank shell and the upstanding rim of a roof therein.

It is a further object of the invention to provide in an arrangement of the type described, a unique mounting structure which accommodates improved floating roof operation under all roof conditions.

These and other objects of the invention will become apparent in the course of the following description, and from an examination of the associated drawings, wherein:

FIGURE 1 is a plan fragmentary view of a floating roof storage tank incorporating the invention.

FIGURE 2 is a sectional view taken along lines 2—2 of FIGURE 1,

FIGURE 3 is an enlarged, detailed sectional view of certain structure shown in FIGURE 2,

FIGURE 4 is a detailed view of certain of the connection means employed,

FIGURE 5 is a sectional view similar to FIGURE 2 of a modified embodiment of the invention,

FIGURE 6 is a detailed view of certain connection means employed in the embodiment of FIGURE 5,

FIGURE 7 is a side elevational sectional view of the anti-turning arrangement employed,

FIGURE 8 is a sectional view taken along lines 8—8 of FIGURE 7, and

FIGURE 9 is a sectional view similar to FIGURE 6 of a slightly modified arrangement.

Describing the invention in detail, and directing attention first to FIGURE 1, it will be understood that the numeral 2 indicates a steel shell of the cylindrical steel storage tank. The numeral 4 designates a conventional floating roof normally disposed in the shell and arranged to float on product stored therein. The roof 4 is provided with an annular peripheral rim 6 which upstands from the edge thereof and defines, with the shell plate 2, an annular space surrounding the roof 4, such space being denoted 8 in the drawing.

To provide a seal for the annular space 8, the invention prescribes a plurality of horizontally aligned, elongated, hollow, closed-end flexible tubes 10, 10 which are arranged within the space 8 intermediate the shell plate 2 and the rim 4. Considering FIGURE 2 specifically, it will be noted that the tube 10 has provided thereon a continuous lip 12 adjacent the upper portion thereof. The lip 12 may be arranged to overlay a flange 14 which forms the top of the rim 6. To attach the lip 12 to the flange 14, elongated clamping bars 16 are provided which are bolted to the flange 14. Thus, the upper portion of the sealing tube 10 is securely fastened to the upper edge of the rim 6.

Turning to FIGURE 1, it will be apparent that adjacent abutting ends of each tube 10 a cylindrical fabric 20 is provided to telescopically receive said adjacent ends. To provide mechanical connection between the tubes 10, the fabric 20 may be secured to the received adjacent ends in any suitable manner, as by cementing or vulcanizing. In this manner, a unitary seal is provided which extends around the entire periphery of the roof. Thus, the

2

seal illustrated is made up of a plurality of individual tubes 10 which must be individually inflated, as herein-after explained. However, if desired, a unitary tube may be provided having a common chamber around the entire roof, as hereinafter discussed.

To accommodate tube inflation, each tube 10 is provided with suitable inflating means 22 which may be a conventional valve or the like. To provide for effective sealing, each tube 10 is inflated to a common level above atmospheric pressure, whereby it will be brought into pressured engagement with the inner surface of the shell plate 2 and the outer surface of the rim 6. In this manner, an effective seal is provided for the space 8.

Those familiar with the art will understand that the roof 4 will, of course, rise and fall within the tank shell 2 in response to a change in liquid level therein. During upward movement of the roof, the connection to the upper edge of the rim at 12 and 14 will be able to maintain the sealing tube 10 in proper physical disposition within the space 8. However, because of the pressure provided within each tube 10, frictional contact between the outer surface of the tube 10 and the inner surface of the shell plate 2 upon downward movement of the roof creates a considerable drag upon each tube section.

25 To avoid the tube rolling out of the space 8 and upwardly upon downward movement of the roof, a one-way driving connection indicated generally at 24 is provided. The location and manner of providing a drive connection 24 is of particular importance in the effective operation of 30 the seal arrangement disclosed. Specifically, the one-way drive connection 24 comprises an upwardly facing hook member 26 which can be seen in FIGURE 4. As disclosed in FIGURE 3, the hook member 26 is connected to a flexible mounting member 28, which may be of any 35 suitable fabric, and overlies the base plate 30 of the hook member 26 and extends above and below same, as is shown in FIGURE 3. The fabric mounting member 28 may be provided with an aperture to allow the upwardly facing hook portion to extend therethrough. The 40 fabric mounting member 28 is then secured to the pressure seal tube 10 in any convenient manner, such as by cementing or vulcanizing.

Those skilled in the art will understand that the roof 4 in arrangements of the type here under consideration frequently are biased out of a central location in the shell by 45 action of the wind or the like thereon. With this in mind, the particular location of the drive arrangement 24 accommodates considerable side or lateral flexibility in each tube 10. This will cause the tubes to expand considerably when the space 8 increases. Further, the one-way 50 drive connection 24 is such that will easily maintain each section of the tube 10 in proper location in the space 8 during downward roof movement. On the rim 6, a continuous angle 31 is mounted so that the outer flange thereof overlies the upwardly facing hook portion 26. Thus, 55 though contact will be maintained, pressured contact between the hook 26 and angle 31 will only occur on downward roof movement. The particular hook-like arrangements 26 may be intermittently located on the tubes 10 as, for example, on twenty-four inch centers. The continuous angles 31 will respectively register with all of the 60 upwardly facing hook-like portions 26 regardless of any lateral shift of the tubes on the rim. It will also be understood that the tube 10, being made up of individual segments, will provide an added pressure differential on 65 opposed sides of the roof to aid in bringing the roof to a central position in the tank.

Attention is now directed to FIGURES 7 and 8 which illustrate an anti-roof turning arrangement that may be employed. Specifically, the anti-roof turning arrangement comprises a bar 32 fixedly secured to the inside of 70 the shell 2. A shoe or shoe member 34 having an elong-

gated aperture therein 36, which is arranged to complemently straddle the bar 32, preferably extends from a point at or near the top of the tube 10 to a point at or near the bottom of same, as is illustrated in FIGURE 7. An upper strap, preferably of flexible material such as leather or fabric, is connected at its opposite ends to the shoe member 36 and to the upper edge of the rim 12, and is indicated at 40. A second strap 42, of similar material, has its opposed ends connected to the lower end of the shoe 36 and to the floating roof 4. The pressured flexible bag intimately surrounds and is contoured to the shoe 36 in the areas of engagement therebetween. This is best seen in FIGURE 8. The frictional effect between the contacting bag 10 and shoe 34, together with the positioning effect of the straps 40 and 42, maintains an intimate relationship between the shoe and the bag, and additionally prevents the roof 4 from rotary movement within the shell 2.

Consideration now will be given to FIGURE 9, which illustrates a slightly modified tube connection arrangement. Again, it will be noted that the rim plate 6 is provided with a downwardly extended bar angle 31. A section of the flexible tube 10 immediately below the angle 31 is arranged to wrap around and embrace a flexible cord or cable 50 as at 52. A spring-like flexible clip 54 demountably but securely positions itself around the tube portion 52, and has an upwardly extending element 56 received in the pocket created by the bar angle 31. Of course, a plurality of clips 54 may be provided around the entire periphery of the seal, and the cable 50 may be continuous therearound or sectionalized to accommodate clip mounting. The clip 54 thus described functions to maintain the tube seal 10 in proper position in a manner similar to that earlier described.

Attention is now directed to FIGURES 5 and 6, which illustrate a slightly modified arrangement of the invention herein considered. The tube seal 100 here shown again is continuously distributed around the entire periphery of the roof 4. However, the tube 100 is not made up of individual segments, but rather presents a common chamber 102 around the entire tank shell. With a continuous chamber 102, a single valve or pressurizing point 104 may be provided. Illustrated in the figure is a flexible hose connection 106 communicating with the valve 104 which, in turn, is operatively connected to a coupling arrangement 108 which has in series therein a closable valve 110. A pressure gauge 112 provides for visual determination of the pressure level within the chamber 102. To provide for pressurizing in the chamber 102, alternate methods may be used. For example, the pipe 114 may communicate with a pipe 116 which in turn establishes communication with a manually operated blower 118. A valve 120 may be provided in the pipe 116 to close or open same depending on the use. In addition, a conventional valve connection 122 may also communicate with pipe 114 to provide for a connection to a gas pressure source, such as carbon dioxide, should it be desired to fill the chamber 102 with a non-explosive medium.

FIGURE 6 illustrates a slightly modified one-way drive connection indicated generally at 124. In this embodiment, an angle bar 31 identical with that previously described is attached to the rim 6. However, a flexible tab 128 is conventionally secured to the bag 100, such as by vulcanizing, and a pair of plates 130, 130 are arranged on opposed sides of the flexible tab 128, and bolted thereto as at 132. The inner plate 130 has another angle 131 secured thereto in any conventional manner, as by welding. The angle 131, of course, faces upwardly in opposition to the downwardly facing angle 31. The function of the one-way drive connection is similar to that described in the earlier embodiment. However, the employment of the flexible tab arrangement 128 accommodates greater horizontal flexibility in the one-way drive connection 124 to aid in connection maintenance during all movements of the roof.

From the standpoint of the centering force available during uncentering roof action, it will be noted that in this embodiment provision is made for variation in physical area contact between the tube seal and the tank shell on opposed sides of the roof. This is distinguished from the earlier embodiment wherein the multiple chambered seal arrangement provided both area variation and pressure variation to aid in roof centering.

Another feature illustrated in this embodiment, and one which may be applied to the earlier embodiment, involves the incorporation of a flexible weather shield 136. The weather shield 136 comprises a rigid plate having its opposed ends crimped, as at 137 and 138, to provide for rigidity therein, and additionally to accommodate bolting to the top flange 14 of the rim, as at 16. The weather shield 136 is, of course, peripherally arranged around the entire roof, and extends outwardly from the rim 6 and upwardly therefrom to cover a major portion of the space between the rim 6 and the tank shell 2. The weather shield 136, of course, deflects a major portion of any foreign matter, such as rain, snow or the like, onto the deck and prevents same from engaging the tube seal and ultimately finding its way within the product storage volume. Additionally, the weather shield 136 is sufficiently flexible so that should any portion of it engage the tank shell during uncentering roof movement, it will merely flex upwardly and return to its original position when the roof again becomes centered.

If desired, a roof centering wheel arrangement indicated generally at 140 may also be employed. The arrangement 140 comprises a housing 142 secured to the bottom of the roof 4. A shaft 144 protrudes from the housing 142 and pivotally carries a wheel 146 on its outer end immediately adjacent the tank shell 2. The shaft 144 is provided with a collar 148 which will be telescopically received within the housing 142, and which in turn engages a spring 150 disposed within the housing 142 to normally bias the shaft 144 and carried wheel 146 outwardly toward the tank shell. During severe uncentering roof action, the wheel 146 will engage the tank shell 2, compressing the spring 150 and providing an additional force to return the roof to a substantially central position within the tank shell.

Thus, it will be seen that I have provided novel pressure tube seal arrangements which effectively seal the annular space between the floating roof and a tank shell, and in addition provides a pressure to maintain the roof centrally located in the tank. It will also be noted that temperature rise of the surrounding atmosphere will heat the gas in each tube section 10, causing an increased pressure therein which increases the effectiveness of the seal. If desired, the gas used in inflating tube sections 10 may be non-inflammable variety such as carbon dioxide which would tend to reduce the possibility of possible incidence of fire hazard in the tank.

The invention as shown is by way of illustration and not limitation, and may be subject to various modifications without departing from the spirit thereof or the scope of the appended claims.

What is claimed is:

1. A floating roof gas seal arrangement comprising a cylindrical tank shell; a roof arranged to float on liquid within the shell; said roof having an upstanding rim peripherally arranged thereon, said rim defining with the shell an annular space around the entire roof; and seal means to close said annular space comprising a flexible pressurized tube disposed throughout said annular space, first mounting means to connect an upper portion of the tube to the upper portion of the rim, a one-way drive connection attaching an intermediate portion of the rim to an intermediate portion of the tube adjacent the rim as seen in side elevation view, said one-way drive connection including a flexible tab attached to the tube, mounting means secured to the tab and spaced from said tabbed attachment to the tube, an upwardly facing hook means

fixedly connected to said mounting means, and a continuous downwardly facing angle means secured to the rim for registering with said upwardly facing hook means.

2. In a sealing arrangement of the type including a floating roof having a peripheral rim located on a liquid contained in a tank shell; a gas sealing means carried solely by said floating roof so as to be positioned between the upstanding roof rim and the tank shell for movement vertically along the tank shell, said gas sealing means comprising a flexible tube means made of a material having gas impervious and wear resistant properties, a gas at relatively low pressure disposed within said tube means maintaining it in an inflated condition, said tube means when inflated being dimensioned and configured so as to form a vertically elongated section disposed between said roof rim and tank shell when the rim and shell are spaced normally apart, and means including means supported from said roof rim connected to vertically spaced apart sections of the inwardly related surface of the tube means for maintaining the tube means in its vertically elongated sectional shape in sealing engagement with the roof rim during vertical movement of the roof, said sections being spaced apart more than 20% and less than 50% of the circumference of the cross-section of the tube means, said gas coacting with said tube means to cause a substantial portion of the inwardly related surface of the tube means to frictionally engage at all times the roof rim, said gas and tube means coacting to cause a substantial portion of the outwardly related surface of the tube means to engage the tank shell when the roof rim is normally spaced from the tank shell and to cause a greater or lesser portion of said outwardly related surface to engage the tank shell at all times when the roof is less than or more than normally spaced from said tank shell.

3. In a sealing arrangement of the type including a floating roof having a peripheral rim located on a liquid contained in a tank shell; a gas sealing means carried solely by said floating roof so as to be positioned between the upstanding roof rim and the tank shell for movement vertically along the tank shell, said gas sealing means comprising a flexible tube means made of a material having gas impervious and wear resistant properties, a gas at relatively low pressure disposed within said tube means maintaining it in an inflated condition and imparting substantial horizontal flexibility to said tube means for the purpose of maintaining an effective vapor seal between said tank shell and tube means irrespective of spacing variations between the roof rim and tank shell encountered during vertical movement of the roof, said tube means when inflated being dimensioned and configured so as to be resiliently disposed between said roof rim and tank shell during vertical movement of the roof irrespective of the spacing variations between the roof rim and tank shell, and means including first and second spaced apart means connected to vertically spaced apart sections of the inwardly related surface of the tube means to maintain the tube means in its resilient position in sealing engagement with the roof rim during vertical movement of the roof, said gas, tube means, and connecting means coacting to cause a substantial portion of the inwardly related surface of the tube means to frictionally engage at all times the roof rim, said gas and tube means coacting to cause a substantial portion of the outwardly related surface of the tube means to engage the tank shell when the roof rim is normally spaced from the tank shell and to cause a greater or lesser portion of said outwardly related surface to engage the tank shell at all times when the roof is less than or more than normally spaced from said tank shell.

4. A floating roof gas sealing arrangement comprising a tank shell for containing liquid; a floating roof located on said liquid in said shell and including a peripheral upstanding rim; gas sealing means positioned between

the upstanding portion of the roof and the tank shell, said gas sealing means comprising a flexible tube means carried by the upstanding rim of the roof, said tube means being made of a gas impervious and wear resistant material for containing a gas, a gas located within the tube means maintaining it in an expanded condition so that when the roof rim and the tank shell are normally spaced apart a substantial portion of its outwardly related surface frictionally engages the tank shell and a substantial portion of its inwardly related surface at all times frictionally engages the rim of the roof, first mounting means connecting an upper section of the inwardly related surface of the tube means to the rim of the roof and operable to maintain the tube means between the rim of the roof and the tank shell during upward movement of the roof, a second mounting means spaced vertically from said first mounting means attaching another section of the inwardly related surface of the tube means to the rim of the roof and including an interlocking flange means on said roof rim and tube seal, the second mounting means being operable to maintain the tube seal between the rim of the roof and the tank shell during downward movement of the roof.

5. The sealing arrangement of claim 4 wherein the interlocking flange means comprises downwardly extending hook means suitably secured to the rim of the roof and, further, an upwardly extending hook means suitably secured to the tube means, the hook means being maintained in assembled interlocking relation by the coaction of the tube means and the first mounting means.

6. A floating roof gas sealing arrangement comprising a tank shell containing liquid; a floating roof located on said liquid and including a peripheral upstanding rim; a gas sealing means carried solely by said floating roof so as to be positioned between the upstanding roof rim and the tank shell for movement vertically along the tank shell, said gas sealing means comprising a flexible tube means made of a material having gas impervious and wear resistant properties, a gas at relatively low pressure disposed within said tube means maintaining it in an inflated condition, said tube means when inflated being dimensioned and configured so as to form a substantially vertically elongated section when disposed between the normally spaced roof rim and tank shell, and means including means supported from said roof rim connected to vertically spaced apart sections of the inwardly facing surfaces of the tube means, said last mentioned means tending to maintain the tube means in its vertically elongated sectional shape during vertical movement of the roof in sealing engagement with both the roof rim and the tank shell irrespective of the relative distance between the roof rim and the tank shell, said sections being spaced apart more than 20% and less than 50% of the circumference of the cross-section of the tube means, said gas coacting with said tube means to effect a horizontal flexibility of the tube means for accommodating variations in distance between the roof rim and the tank shell during vertical movement of the roof.

7. In a sealing arrangement of the type including a floating roof having a peripheral rim located on a liquid contained in a tank shell; a gas sealing means carried solely by said floating roof so as to be positioned between the upstanding roof rim and the tank shell for movement vertically along the tank shell, said gas sealing means comprising a flexible tube means made of a material having gas impervious and wear resistant properties, a gas at relatively low pressure disposed within said tube means maintaining it in an inflated condition and imparting substantial horizontal flexibility to said tube means for the purpose of maintaining an effective vapor seal between said tank shell and tube means irrespective of spacing variations between the roof rim and tank shell encountered during vertical movement of the roof, said tube means when inflated being dimensioned and configured so as to be resiliently disposed between said roof rim and tank shell during vertical movement of the roof irrespec-

tive of the spacing variations between the roof rim and tank shell, and means connected to and supported by said roof rim and including first and second spaced apart means connected to vertically spaced apart sections of the inwardly related surface of the tube means to maintain the tube means in its resilient position in sealing engagement with the roof rim during vertical movement of the roof, said gas, tube means, and connecting means coacting to cause a substantial portion of the inwardly related surface of the tube means to frictionally engage at all times the roof rim, said gas and tube means coacting to cause a substantial portion of the outwardly related surface of the tube means to engage the tank shell when the roof rim is normally spaced from the tank shell and to cause a

greater or lesser portion of said outwardly related surface to engage the tank shell at all times when the roof is less than or more than normally spaced from said tank shell.
